United States Patent Office

Des. 204,458
Patented Apr. 19, 1966

204,458

PUNCHED CARD READER OR SIMILAR ARTICLE

William H. Harkins, Lexington, and Joseph R. Bachman II, Framingham, Mass., assignors to Honeywell Inc., Minneapolis, Minn., a corporation of Delaware

Filed Feb. 16, 1965, Ser. No. 83,829

Term of patent 14 years

(Cl. D26—5)

Fig. 1

Fig. 2

Fig. 3

FIGURE 1 is a perspective view of the top, front and right side of a punched card reader or similar article embodying our new design.

FIGURE 2 is a perspective view of the top, rear and left side thereof.

FIGURE 3 is a plan view thereof.

The dominant features of the claimed design reside in the portions shown in solid lines in the drawings, the stacks of cards being shown in broken lines for illustrative purposes only.

We claim:

The ornamental design for a punched card reader or similar article, substantially as shown and described.
